UNITED STATES PATENT OFFICE.

FRANK A. DELPH, OF NEW ORLEANS, LOUISIANA, ASSIGNOR OF ONE-HALF TO BROOKS A. COLOMB, OF COLOMB, LOUISIANA.

HEATING ATTACHMENT FOR GRATES AND FIREPLACES.

No. 877,303.

Specification of Letters Patent.

Patented Jan. 21, 1908.

Application filed June 25, 1907. Serial No. 380,736.

To all whom it may concern:

Be it known that I, FRANK A. DELPH, a citizen of the United States, and a resident of New Orleans, in the Parish of Orleans and State of Louisiana, have invented an Improved Heating Attachment for Grates and Fireplaces, of which the following is a specification.

My invention is an improvement upon that 10 for which I filed an application for Patent No. 342,988, on November 12, 1906.

In my former invention I have attached U-shape return flues or pipes to a plate adapted to cover the upper portion of a fire-place or grate front, the same being hinged 15 at one side so as to swing laterally and thus open the space above the grate or fire-hearth whenever required. When the said plate is closed and a baffle plate is arranged in the 20 fire space behind it, the products of combustion are directed through the flues or pipes and thus the latter become effective for heating an apartment with a comparatively small consumption of fuel.

25 My present invention is embodied in an attachment for the fireplace, or grate, frame, the same consisting of a supplemental frame, to which the plate having the heating flues or pipes attached is hinged so as to swing laterally thereon.

The invention further includes an improved means for securing such supplemental frame to the main frame, and anchoring both frames to the fireplace wall. The baffle plate 35 is normally supported upon such anchoring devices and is connected with the hinged grate front so as to be drawn upward to a vertical position when the grate front is swung laterally.

40 The details of construction, arrangement, and operation of parts are as hereinafter described and illustrated in the accompanying drawing, in which—

Figure 1 is a front view of a grate or fire-place front showing my improved attachment. Fig. 2 is a vertical transverse section on the line 2—2 of Fig. 1. Fig. 3 is a perspective view of the supplemental frame and anchoring device attached thereto. Fig. 4 is a horizontal section taken above the baffle plate when lying in working position.

A indicates a grate, and B a frame such as ordinarily employed in connection therewith. C indicates the plate which is adapted to 55 close the space above the grate A, and to

which the U-shaped return flues or pipes D are attached as in my former invention. In this instance, in place of hinging such plate C on the frame B, I provide a supplemental frame E, shown detached in Fig. 3, the same 60 being fitted and secured to the upper portion of the fireplace frame B. In this instance such upper portion of the frame B describes a semicircle, but it may of course be rectangular, or have any other preferred form. In 65 all cases the supplemental frame E will conform to the shape or contour of the inner portion of such frame B. In this instance, therefore, it is semicircular as shown. Such frame is provided on the front with a rib and 70 with an exterior flange e that extends over the edge of the frame B. For securing it to such frame and for anchoring both frames B and E, I provide the attachment F applied to frame E, see Figs. 2 and 3, the same 75 consisting of a metal bar having a front flange or lug f which is provided with holes for reception of bolts or rivets that secure it to a lug e² formed on and projecting laterally from the inner flange e' of the supplemental frame E. 80 Directly in rear of such flange, the bar F is provided with another, f' which projects from the back of the same and is in contact with the rear side of the grate frame B; see especially Fig. 4. Thus, when the bar F is securely attached to the lug e², the rear lug f' is drawn tightly against the fireplace frame B and held securely in place. The inner flanged end f² of bar F is in practice anchored 85 in the wall of the fireplace. Two holes are 90 provided in the bar F, near its inner end to receive nails or spikes for holding the bar to the brick nook. The ends of the supplemental frame are provided with toes or feet e⁵, which as shown in Fig. 1, rest upon the top 95 bar on the grate A.

The swinging plate C is hinged to lugs e³ cast integrally with the frame E.

In Fig. 1 the plate C with its attached flues or pipes D is shown swung off laterally; but in 100 Figs. 2 and 4 it is shown in a closed position, in which case it fits within the rib e⁴ formed on the front of the supplemental frame E. For fastening it in this position, I employ a device consisting of a rotary handle G, having on its inner end a prong or finger g, which, when the handle is turned to the vertical position, engages the inner side of the grate frame B as shown in Fig. 2.

In addition to anchoring the frames B, E, 110

and securing them together as before stated, the bars F, which, as shown in Fig. 4, are directly opposite each other on the sides of the fireplace or grate opening, serve as rests and supports for the division, or baffle, plate H. In Figs. 2 and 4 such plate is shown in its normal position or resting upon the bars F whereby it serves to interrupt the direct upward course of the flame or products of combustion from the fuel burning in the grate, so that they are compelled to pass through the return flues D as indicated by arrows Fig. 2. It is obviously necessary, however, that such plate shall be raised, and thus allow free upward passage of flame and gaseous products of combustion whenever the grate or fireplace front C with its attached flues is swung off laterally as in Fig. 1. I have, therefore, provided means whereby such baffle plate H will be raised automatically whenever the front is swung off. The means consists of a bar or rod I, which is pivotally connected with the plate C on the left side near the top, as indicated in Fig. 1, and at its other end with the rear side of the baffle plate near its middle. Thus the baffle plate will be raised and lowered automatically according to the movement of the plate C in opening or closing. It will be noted that the vertical side flanges f^3 of the bars F prevent endwise movement of the baffle plate H, and the front flanges f also prevent it being drawn forward in the act of rising or falling.

What I claim is—

1. The combination, with the fireplace frame and a supplemental frame applied to the upper front portion of the same, of an anchoring device consisting of a bar secured at its front end to the supplemental frame and extended rearward therefrom substantially as described.

2. The combination, with the fireplace frame and the supplemental frame applied to its upper portion on the outer side, of a bar secured to the supplemental frame and extending inward therefrom, said bar being provided on its rear side with a lateral lug adapted to engage the fireplace frame and thus hold the supplemental frame in place, substantially as described. 45

3. The combination, with a fireplace frame and a supplemental frame secured thereto and having inwardly extended bars and a baffle plate adapted to rest on such bars, substantially as described. 50

4. The combination, with the fireplace frame and a supplemental frame applied thereto, of rearwardly extended bars secured to said supplemental frame, a baffle plate resting normally on these bars, a front plate hinged on the supplemental frame and means for loosely connecting it with the baffle plate whereby when the front plate is swung out laterally the baffle plate is raised 60 as shown and described. 65

5. The combination, with a fireplace frame and a supplemental frame attached to the upper portion thereof, a front plate hinged on the supplemental frame and adapted to swing laterally, bars attached to the sides of the supplemental frame and extending inward therefrom, the same having side flanges f^3 , a baffle plate adapted to rest on said bars and to close within the said flanges and means for connecting the baffle plate with 70 front the swinging plate, substantially as described. 75
